CLAIM

The ornamental design for the bottle cap, as shown and described.

DESCRIPTION

FIG. 1 is a perspective view of a bottle cap, showing my new design;

FIG. 2 is a first side elevational view thereof;

FIG. 3 is a second side elevational view thereof;

FIG. 4 is a third side elevational view thereof; and

FIG. 5. Is a fourth side elevational view thereof.

FIG. 6 is a top plan view thereof; and,

FIG. 7 is a bottom plan view thereof.

The broken lines are shown for the purpose of illustrating parts of the article that form no part of the claimed design.

1 Claim, 4 Drawing Sheets
